UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,096,120.

Specification of Letters Patent. Patented May 12, 1914.

Application filed September 25, 1913. Serial No. 791,718.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft gear having a preliminary spring, and in which the preliminary spring operates independently of the main springs and friction devices of the gear.

In the drawings forming a part of this specification, Figure 1 is a side elevation partly in central longitudinal section of a draft gear embodying my invention. Fig. 2 is a front end view thereof. Fig. 3 is a rear end view thereof. Fig. 4 is a perspective view of the preliminary follower. Fig. 5 is a perspective view of the washer employed in said gear.

Referring to the drawings, 6 illustrates a shell, preferably cylindrical in shape or circular in cross section, open at its forward end and provided near its rear end with a preferably integral partition 7, in front of which are deposited the main cushioning devices hereinafter described, and back of which is mounted the preliminary cushioning device hereinafter described. The main cushioning members consist of friction mechanism and the main springs 8, preferably comprising an outer spring 9, and an inner spring 10, nested therein. The said springs are forwardly seated against the friction mechanism.

The friction mechanism comprises the friction shoes 11, which are preferably three in number, each having an outer friction face 12, and an inner wedging face 13. A wedge 14, preferably pyramidal in form, and adapted to separate the friction shoes, is provided with wedging faces 15, equaling in number the friction shoes, there being an anti-friction roller 16, disposed between each wedging face of the wedge and the adjacent wedging face of the friction shoe. The wedge is forwardly provided with a recess 17, to receive the nut 18, of the connecting

rod 19, which passes through the wedge and engages the preliminary follower 20 herein-after described. The preliminary follower 20 consists of a plate 21, forwardly provided with a collar 22, having a shoulder 23, 60 adapted to engage on its extreme forward movement the rear end 24 of the shell, the said collar being adapted to reciprocate within the rear chamber 25 of the shell back of the partition 7 therein. The said follower is centrally provided with a forwardly extending spindle 26, which passes through a perforation 27 in the partition 7 of the shell, and is provided with a rear-wardly opening recess 28, within which the head 29 of the connecting rod 19 is received; the said connecting rod passing through the perforation 30 in the said spindle. Near its forward end the spindle 26 is provided with an annular groove 31, adapted to receive the 70 'I shaped clip or washer 32 illustrated in Fig. 5 of the drawings. The said washer 32 in preferable construction is provided with an inwardly extended lug 33 which engages within the groove 31 of the spindle, 75 and an annular portion 34 in front of said lug engaging against the boss 35 at the forward end of the said spindle 26. In preferable construction the flange or lug 33 of the washer 32 is of lesser width than the 80 annular groove 31 in the spindle 26, leaving a space as indicated at the numeral 37 in Fig. 1 of the drawing to permit the forward movement of the spindle without moving the said washer forwardly. Although 85 it will be apparent that on forward movement of the said spindle the washer could be forced forwardly employing the inner spring 10 in connection with the preliminary spring hereinafter described, I prefer that 90 the space 37 substantially corresponds with the space 38 between the front edge 39 of the collar of the preliminary follower and the partition 7 of the shell in the normal 95 position of the parts of the gear.

The outer main spring 9 is rearwardly seated against the rear partition wall 7 of the shell and around the washer 32. The outer spring 9 serves to lock the washer 32 securely in position when the same is keyed 100 to the spindle 26. Seated against the pre-liminary follower at their rear ends and within the collar of said rear follower are the preliminary springs 40, preferably comprising an outer spring 41 and an inner 110

spring 42 nested therein, the same surrounding the spindle 26 of the preliminary follower and forwardly seated against the rear face of the partition wall 7 of the shell. It will be apparent that in this structure the preliminary spring is arranged independently of the main spring, and that the preliminary movement of the gear through the action of the preliminary spring can be predetermined and fixed.

In assembling the parts of the gear the preliminary springs and preliminary follower are placed in position at the rear end of the shell, and the washer is then inserted through the forward end of the shell and placed in engagement with the said spindle to lock the same, as hereinbefore described. The main springs and the friction elements are then placed in position and the retaining rod inserted.

I claim:

1. In a draft gear combination and shell friction mechanism, a spring within the shell, a preliminary follower and preliminary springs seated between the follower and the shell, the said follower being provided with a forwardly extending spindle passing within the shell, and having means to slidely lock said spindle to the shell.

2. In a draft gear a shell friction mechanism and springs within the shell, a preliminary follower, a preliminary spring seated between the shell and said follower, and a locking washer; the shell being provided with a transverse partition, the follower having a forwardly extended spindle passing through said partition and the locking washer, securing said spindle within the shell.

3. In a draft gear, a friction device including a shell, a preliminary follower spring seated between said follower and shell, the follower being provided with a projection and a lock washer slidely engaging said projection within the shell.

4. In a draft gear combination, a shell friction mechanism and springs within the shell, a preliminary follower, preliminary springs seated between said follower and the shell, a locking washer, the said preliminary follower having a forwardly extended spindle and groove in said spindle to receive said washer, whereby the preliminary springs may be held under an initial compression.

JOHN F. O'CONNOR.
